US00D882723S

(12) **United States Design Patent** (10) Patent No.: **US D882,723 S**
 Burrow et al. (45) Date of Patent: ** *Apr. 28, 2020

(54) **AMMUNITION CARTRIDGE**

(71) Applicant: **TRUE VELOCITY IP HOLDINGS, LLC**, Garland, TX (US)
 (72) Inventors: **Lonnie Burrow**, Carrollton, TX (US); **Christopher William Overton**, Richardson, TX (US)

(73) Assignee: **TRUE VELOCITY IP HOLDINGS, LLC**, Garland, TX (US)

(*) Notice: This patent is subject to a terminal disclaimer.

(**) Term: **15 Years**

(21) Appl. No.: **29/644,863**

(22) Filed: **Apr. 20, 2018**

(51) LOC (12) Cl. **22-03**

(52) U.S. Cl.

USPC **D22/116**

(58) **Field of Classification Search**

USPC D22/115, 116; D11/143; D7/619.1

CPC F42B 5/26-38; F42B 33/00; F42B 8/14

(57) **CLAIM**

The ornamental design for an ammunition cartridge, as shown and described.

DESCRIPTION

FIG. 1 is an isometric view of an ammunition cartridge showing my new design.

FIG. 2 is a top view of the ammunition cartridge of FIG. 1.

FIG. 3 is a cross-sectional view taken along line 3-3 in FIG.

2 of the ammunition cartridge of FIG. 1; and,

FIG. 4 is a side view of the ammunition cartridge of FIG. 1. The broken lines depict portions of the ammunition cartridge that form no part of the claim.

1 Claim, 4 Drawing Sheets
